UNITED STATES PATENT OFFICE

MAURICE KEATING, OF SALT LAKE CITY, UTAH, ASSIGNOR TO NEON ARROWLITE, INC.,
OF SALT LAKE CITY, UTAH, A CORPORATION OF UTAH

DESIGN FOR AN AUTOMOBILE DIRECTION SIGNALING LIGHT

Application filed March 11, 1931. Serial No. 39,032. Term of patent 14 years.

To all whom it may concern:

Be it known that I, MAURICE KEATING, a citizen of the United States, residing at Salt Lake City, in the county of Salt Lake and State of Utah, have invented a new, original, and ornamental Design for an Automobile Direction Signaling Light, of which the following is a specification, reference being had to the accompanying drawings, forming part thereof.

In the drawings Figure 1 is a top view of my automobile direction signaling light; and Figure 2 is a front view thereof.

I claim:

The ornamental design for an automobile direction signaling light, as shown.

In witness whereof, I hereunto subscribe my name this 4th day of March, 1931.

MAURICE KEATING.
